UNITED STATES PATENT OFFICE.

HENRY FIELD BLACKWELL, JR., AND MAUDE ALICE BLACKWELL, OF NEW YORK, N. Y.; SAID HENRY FIELD BLACKWELL, JR., ASSIGNOR TO SAID MAUDE ALICE BLACKWELL.

TELEPHONE.

SPECIFICATION forming part of Letters Patent No. 630,797, dated August 8, 1899.

Application filed December 24, 1898. Serial No. 700,261. (No model.)

To all whom it may concern:

Be it known that we, HENRY FIELD BLACKWELL, Jr., and MAUDE ALICE BLACKWELL, of the city of New York, borough of Manhattan, in the county of New York and State of New York, have invented a new and Improved Telephone, of which the following is a full, clear, and exact description.

This invention relates to improvements in telephones; and the object is to provide a telephone of small and compact form that may be readily carried in a person's pocket and adapted to be attached to a fire-alarm system or circuit without impairing or cutting out the circuit for fire-alarm purposes, and is designed to facilitate operations of the fire-department and its officers in the execution of their various duties by superseding the existing system of telegraphing, code-signals, and Morse characters.

We will describe a telephone embodying our invention and then point out the novel features in the appended claims.

Reference is to be had to the accompanying drawings, forming a part of this specification, in which similar characters of reference indicate corresponding parts in all the figures.

Figure 1 is a front elevation of a telephone embodying our invention and showing the same as attached to a fire-alarm box. Fig. 2 is a front elevation of the telephone drawn on a larger scale than that in Fig. 1. Fig. 3 is a longitudinal section of a receiver employed, and Fig. 4 is a diagrammatic view illustrating the circuits.

The telephone comprises a casing 1, provided with a swinging door 2 and having a bail 3, adapted to be engaged over the inner door 4 of a fire-alarm box 5—that is, the bail has a hook portion at its top to engage over the top of the alarm-box door—and as the top of said door is curved it is obvious that the telephone will not only be suspended, but will be prevented from slipping laterally. Arranged within the casing is the diaphragm 6 for the transmitter, and also arranged in the casing is a battery 7, preferably of the dry type, having spring connections or contacts with the primary circuit. Also arranged within the casing are a condenser 8 and an induction-coil comprising the primary 9 and the sec-

ondary 10. The primary of the circuit is contained entirely in the case of the telephone, excepting where the wire loops pass out into the receiver through the receiver-core 11. 55

The receiver comprises a casing 12, within which are the coil 13, the steel core 14, and the diaphragm 15. The coil 13 and core are surrounded by a steel thimble 16, which is in magnetic connection with the core 14. Connected to the diaphragm end of the receiver is an earpiece 17, here shown in the form of a bent tube, and it is designed to have its end placed within the ear, so that the operator will not be disturbed by other sounds on the 65 street.

A switch is arranged within the receiver, and consists of a spring-arm 18, adapted to be pushed into engagement with the contact-point 19, and extended outward from the 70 spring 18 is a push-button 20. The switch of course is located in a primary circuit, and when it is desired to leave the instrument in circuit and not in use by releasing the button 20 the spring 18 will move to its open position, so that there can be no waste of the 75 battery.

Having connection with the secondary circuit is a jack-plug 21, consisting of a central pin surrounded by a sleeve of insulating material, separating the pin from the outer conducting-sleeve. A socket 22 for receiving the jack-plug is arranged within each fire-alarm box and has two connections, one of which (indicated at 23) has connection with 85 the main fire-alarm line 24, and the other, 25, leads to the ground. These connections are normally open; but when the jack-plug is inserted in the socket to place the secondary circuit in the telephone in electrical connection with the fire-alarm circuit and with the ground through the condenser 8 without placing a ground on the wire one wire 26 of the secondary leads to the outer shell of the jack-plug 21 and the other wire 27 leads to the 95 inner pin of the jack-plug.

In operation when it is desired to telephone to headquarters or to any other place on the line the jack-plug is to be inserted in the socket 22 and the instrument hung upon the 100 inner door of the fire-alarm box, as plainly indicated in Fig. 1. Then by placing the re-

ceiver to the ear and closing the switch the circuit is complete, so that conversation may be had through the telephone.

While we have described the instrument as particularly adapted for the use of the fire-department, it is to be understood that it will also be useful as an instrument of accuracy in making capacity determination and the other tests for locating faults in underground 10 constructions or overhead work by being used in place of a galvanometer, as at present.

Having thus fully described our invention, we claim as new and desire to secure by Letters Patent—

15 1. A receiver for a telephone, comprising a casing, a coil in the casing, a diaphragm, a metal core in the coil, a metal thimble surrounding the coil and connecting with the core, and a switch in the receiver for control-

ling the primary of the instrument, substantially as specified. 20

2. A receiver for a telephone, comprising a casing, a coil arranged within the casing, a diaphragm, an ear-tube extending from the diaphragm end of the casing, a steel core in 25 the coil, a steel thimble surrounding the coil and having connection with the core, and a switch in the receiver, consisting of a spring-contact and a fixed contact, said contacts being in the primary of the instrument, and a 30 push-button extending outward from the spring, substantially as specified.

HENRY FIELD BLACKWELL, JR.
MAUDE ALICE BLACKWELL.
